UNITED STATES PATENT OFFICE

LAURENCE H. BURNHAM, OF LEXINGTON, MASSACHUSETTS, ASSIGNOR TO THE B. F. GOODRICH COMPANY, OF NEW YORK, N. Y., A CORPORATION OF NEW YORK

METHOD OF MAKING RUBBER BOOTS

Application filed April 15, 1930. Serial No. 444,413.

This invention relates to rubber boots and methods of making the same.

Rubber boots as heretofore manufactured have had the disadvantages of poor ventilation and of sweating the feet, with consequent 5 discomfort to the wearer, especially in hot weather, and in cold weather have provided poor heat insulation, allowing the feet to become cold.

My chief objects are to provide a rubber boot having improved ventilation; to provide a rubber boot having improved heat insulation; and to provide a rubber boot having both of those advantages in combination. A 10 further object is to provide convenient and economical procedure for manufacturing rubber boots having those desirable characteristics.

I attain these objects in the preferred form 20 of my invention by providing a fibrous boot lining of such thickness and of such loose or open structure as to provide ventilation along the inner face of the boot wall, the lining preferably being only adhered to the rubber 25 of the boot wall as distinguished from being embedded in or impregnated by the rubber.

The lining preferably, although not necessarily, is of knitted wool yarn, for warmth in conjunction with the ventilating feature, and 30 for durability.

Of the accompanying drawing:

Fig. 1 is a vertical section of a boot embodying and made in accordance with my invention in its preferred form.

Fig. 2 is a section on line 2-2 of Fig. 1.

Referring to the drawing, the rubber wall of the boot is designated 10, and may be reinforced internally with fabric 11. The thick and permeable lining 12 is shown as 40 being adhered to the inner face of the rubber wall, without extensive penetration of the lining by the rubber, so that the interstices of the lining provide good ventilation to the mouth of the boot in conjunction with good heat insulation.

In order that the lining may be of approximately the same thickness and have good 45 ventilating characteristics throughout, as distinguished from a lining stretched to a thin or an open-mesh condition in local

regions, the lining preferably is pre-formed in approximately the size and shape which it is to have in the finished boot, as by originally knitting it approximately to shape and size, which is best effected by using different types of stitch such as 13 and 14 in the foot and leg portions respectively, and by the use of such different types of stitching the foot portion of the lining may be made of somewhat more compact structure, as shown, 55 for warmth and for good wearing properties, while the leg portion, for the ready passage of air throughout its length, may be made of looser structure. The lining preferably is longitudinally ribbed, which contributes to its ventilating effect.

For durability and exactness of shape the boot preferably is manufactured by pulling the lining onto an expandable last, building the rest of the boot thereon, and then vulcanizing the boot in a mold while it is held distended against the mold by a pressure fluid within the expandable last, although I do not wholly limit my invention to a molded boot as distinguished from a boot vulcanized in 70 open heat.

The high compacting pressure employed in the molding operation makes it desirable to take precaution against such extensive flow of the rubber into the interstices of the lining 80 as would defeat the chief objects of the invention as above set out, and such flow of the rubber may be prevented, for example, by employing, in the inner region of the rubber wall which contacts the lining, a layer of cord 85 fabric 15, the cords preferably extending lengthwise of the boot, to give longitudinal strength as well as to serve as a dam against extensive penetration of the lining by the rubber.

Seams, such as the seams 16, 17, are embedded in and flattened against the rubber in the vulcanizing operation, so that the inner face of the lining is smooth.

A boot manufactured as described has the 95 important advantages set out in the above statement of objects.

I claim:

The method of making a rubber boot which 100 comprises preforming a lining of such thick

and open structure as to provide substantial ventilation through the material thereof and approximately to its final size and shape, pulling the lining onto an expansible last, building upon the lining the other parts of
5 the boot including a layer of material next to the lining adapted to prevent extensive penetration of the lining by the rubber, and, by vulcanizing the boot in a mold while holding it distended thereagainst by pressure
10 fluid in the last, adhering the rubber composition to the lining without such penetration of the rubber into the lining as substantially to reduce the ventilating characteristics of the lining.

15 In witness whereof I have hereunto set my hand this 11th day of April, 1930.

LAURENCE H. BURNHAM.
